(57) **CLAIM**

The ornamental design for an inhaler, as shown and described.

DESCRIPTION

FIG. 1 is a front right perspective view an inhaler in a closed configuration.

FIG. 2 is a rear left perspective view of the inhaler shown in FIG. 1.

FIG. 3 is a front left perspective view of the inhaler shown in FIG. 1.

FIG. 4 is a rear right perspective view of the inhaler shown in FIG. 1.

FIG. 5 is a front view of the inhaler shown in FIG. 1.

FIG. 6 is a rear view of the inhaler shown in FIG. 1.

FIG. 7 is a left side view of the inhaler shown in FIG. 1.

FIG. 8 is a right side view of the inhaler shown in FIG. 1.

FIG. 9 is a top view of the inhaler shown in FIG. 1.

FIG. 10 is a bottom view of the inhaler shown in FIG. 1.

FIG. 11 is a front right perspective view of the inhaler in an open configuration.

FIG. 12 is a rear left perspective view of the inhaler shown in FIG. 11.

FIG. 13 is a front left perspective view of the inhaler shown in FIG. 11.

FIG. 14 is a rear right perspective view of the inhaler shown in FIG. 11.

FIG. 15 is a front view of the inhaler shown in FIG. 11.

FIG. 16 is a rear view of the inhaler shown in FIG. 11.

FIG. 17 is a top view of the inhaler shown in FIG. 11; and,

FIG. 18 is a bottom view of the inhaler shown in FIG. 11.

The broken lines in the figures represent portions of the inhaler that form no part of the claimed design.

1 Claim, 9 Drawing Sheets
